UNITED STATES PATENT OFFICE.

RUSSEL G. WOODWARD, OF WAUKEGAN, ASSIGNOR TO THE UNION SPECIAL SEWING MACHINE COMPANY, OF CHICAGO, ILLINOIS.

DESIGN FOR A FLY-WHEEL FOR SEWING-MACHINES.

SPECIFICATION forming part of Design No. 23,936, dated January 1, 1895.

Application filed November 10, 1894. Serial No. 528,427. Term of patent 14 years.

To all whom it may concern:

Be it known that I, RUSSEL G. WOODWARD, a citizen of the United States, residing at Waukegan, in the county of Lake, State of Illinois, have invented a certain new and original Design for Sewing-Machine Fly-Wheels, of which the following is a description, reference being had to the accompanying drawings, and to the letters of reference marked thereon.

My invention relates to a new and original design for the belt wheels of sewing machines though it will be understood that it is applicable to fly wheels used for other purposes.

15 The invention is illustrated in the accompanying drawings, in which—

Figure 1 is a perspective view of a fly wheel embodying the design, and Fig. 2 is a cross section on the line 2—2 of Fig. 1.

20 The periphery A of this wheel is of the ordinary form and the wheel is provided with a hub B through which is an opening C for the passage of the main shaft of the machine to which the wheel is applied. The rim of the wheel is thicker than the central portion and is beveled inwardly to the central portion, as shown in D. The lower half of the

central portion is formed of a solid web E which, at the center, is beveled inwardly, as shown at b. The upper half of the central portion of the wheel is provided with the solid semi-circular part c having the solid portions d, e connecting the same respectively with the exterior of the hub and the interior periphery of the wheel. Openings F, curved to conform to the shape of the wheel and in extent almost a quadrant of a circle, are formed in the upper part of the wheel above the solid portion a, while between the solid portion and the hub and on either side of the solid projection d are circular, triangular openings f.

Having thus described my invention, what I claim, and desire to secure by Letters Patent, is—

25 The design for a fly wheel or sewing machine belt wheel substantially as shown and described.

In testimony whereof I affix my signature in presence of two witnesses.

RUSSEL G. WOODWARD.
